CORD EDGE BRAID

Herbert C. Mintel, North Attleboro, Mass., assignor to Rhode Island Textile Company, a corporation of Rhode Island

Application April 1, 1941, Serial No. 386,251

7 Claims. (Cl. 96—26)

This invention relates to a braid of a type commonly called cord edge braid by reason of there being a large rounded portion or cord at one edge with a flat braid extending from that edge for attachment of the cord in position. The material is that used for decorative purposes on hats and the like.

The usual cord edge braid consists of a core or warp of a braided structure about which there is braided a covering with a flat braid extending more or less radially therefrom with the flat braid interlocked with the braid of the covering of the warp core. Such material is usually made on a braiding machine designed especially for this purpose and consisting of two braiding tracks which are interlocked in order that the braided yarns of the flat fabric may attach to the braid over the cord.

One of the objects of this invention is to provide a cord edge braid on a machine known as a Vienna or oval braider but modifying the arrangement of the warps of the usual Vienna or oval in such a manner that instead of providing a Vienna braid there will be provided a cord edge braid which will have a structure different from the structure of the cord edge braid provided on the cord edge braider but suitable for the same use.

Another object of the invention is to provide a cord edge braid at a lesser expense than that of the usual cord edge braid.

Another object of the invention is to provide a cord edge braid which may have a color arrangement in the form of a helical stripe rather than an intermingled color arrangement such as would be provided in the usual cord edge braid machine.

With these and other objects in view, the invention consists of certain novel features of construction, as will be more fully described, and particularly pointed out in the appended claims.

In the accompanying drawing:

Fig. 1 is a plan view of one side of my novel construction;

Fig. 2 is a view similar to Fig. 1 showing the opposite side of the braid;

Fig. 3 is a plan view in diagrammatic form showing the paths of the carriers of the Vienna or oval braid machine, and illustrating the position of the cores which I insert in the machine for accomplishing my purpose;

Fig. 4 is a diagrammatic view greatly expanded, illustrating the path of the yarn which goes to form my cord edge braid;

Fig. 5 is a skeleton view of the yarns shown more clearly in their interlocking arrangement and patterned somewhat after the showing in Fig. 4.

This invention modifies the usual braid formed on a Vienna or oval braider by changing the po-

sition of the warps used in a Vienna braider and also the size of the warps which are used, the arrangement being such that a cord edge braid is formed. In the Vienna braider there are two sets of carriers, each with the carriers in its set following its own path of travel. These paths interlock; and in carrying out this invention as shown in Fig. 3, I position a large core within the path of one of these sets of braiders only, and eliminate the usual small core or warp positioned in the end loop of this path; and I position warps of smaller size within the path of the other set of braiders only, whereby my novel result is formed.

With reference more particularly to the drawing, I have shown in Fig. 3 at 10 diagrammatically the path of one set of carriers of the Vienna braider and at 11 the path of travel of the other set of carriers of the Vienna braider. It will be noted that the path 10 provides a loop doubled back upon itself as at 12, and the path 11 provides a loop doubled back upon itself as at 13. Likewise, the path of travel, 10 and 11, overlap one another. Usually at the center location 14 in the usual Vienna braider there is provided a core. Likewise, in the usual Vienna braider at points 15 and 16 within the loops 12 and 13 there are provided cores.

In the construction which I provide, the core or warp at the center location 14 is entirely eliminated, and instead there is provided cores or warps at 16 and 17, both outside of the path 10 but within the path 11. The warps or cores 16 and 17 are of relatively small diameter and are the cores which are positioned in the flat braid portion 20 of my cord edge braid. These cores serve to widen out the flat braid desirable for attachment purposes and hold the flat braid in position as the braid is formed.

In order that the cord may be formed, I locate a large core 18 within the path 10 of one set of carriers but outside of the path 11 of the other set of carriers, I have found by locating this large core in the position shown at 18, as distinguished from within the loop 12, no alterations whatsoever are necessary on the machine. However, it is possible that I may locate the core 18 at the point 15 by some modification of the machine such for instance as rearranging the angularity 50 of the lead from the carrier to the maypole of the braider.

In the structure which I provide, the core 18 consists of a plurality of warp yarns 21 such for instance as sixteen ends of 8/3 ply carded 55 natural cotton yarn about which there has been braided as at 22 a covering such, for instance, as two ends of a 300 denier colored rayon yarn. This may be covered on a sixteen carrier machine. These specifications, however, may be varied as will be readily apparent. The cores 16

and 17 will be considerably smaller and may consist of 20/2 ply KP white cotton yarn twisted.

The set of carriers which form the helically disposed covering of yarn 23 will carry a colored yarn which may be two ends of 300 denier vat dyed yarn and may be of any color desired, but preferably of a similar color to that covering the core 18. The carriers which would be used to travel the path 10 would be equal to the number of carriers which would travel the path 11; and for the structure of yarn which I have above illustrated, I would use nine carriers in each set. The carriers which carry the yarn 23 will each wrap the yarn helically, as shown at 23, about the core 18, as shown in Fig. 3; while the carriers which travel the path 11 will carry, for the sake of the illustration which carries through this specification, although it clearly may be modified, 20/2 ply KP mercerized white yarn. They will wrap a layer of yarn as at 24 about the warp or core 16 and will braid an intermediate section as at 25 between this wrapping and the wrapping 23, as illustrated in Fig. 1, which will embrace the core or warp 17.

In the arrangement which I have illustrated, and as seen in Fig. 3, there will be an interlocking of the colored yarns 23 and the white yarns 24, 25, some of the color being apparent at the crossings in the shaded position shown at 26, and there being formed a rib of interlocked yarns at 27 which roll over close to the junction of the flat braid, designated generally 20, and the cord edge of the braid designated 28.

From the showing in Fig. 4, it will be apparent that one of the colored yarns, as 23, here designated 23', will emerge from the flat braid, extend about the core 18, returning as shown at the dotted line, also designated 23', and then interlock with the yarns from the path 10, as at 30 and 31, by extending beneath two of these yarns and then as at 32 and 33 by extending over two of these yarns, and then entering the fabric formed by the carriers in path 11 as at 34, after which it again emerges in a further repeat.

Each of the colored yarns follows this cycle of repeats in its path in the fabric, it being apparent that, there being nine carriers, the repeat will exist every nine helical wraps of the yarn about the cord core 18. It will be readily apparent that, if I employ different colors of the yarn on the carriers in the path 10, each of the colors will show up as a helical wrap in the yarn 23 about the cord which forms the edge of the fabric. I may, for instance, select three successive carriers of one color and six carriers of another color, whereby there would be a helical stripe formed one-third the color of the three carriers and two-thirds the color of the six carriers.

I claim:

1. A cord edge braid comprising a plurality of cores, the core adjacent one edge being larger than the other cores, a plurality of yarns wrapped about the larger core with each of said yarns lying on said core parallel to each other, and a plurality of different yarns wrapped about the core at the other edge of the braid and extending in braid formation between the two wrappings with the wrapped yarns about the larger core interlocked in braid formation with the braided portion between the wrappings.

2. A cord edge braid comprising a plurality of cores, the core adjacent one edge being larger

than the other cores, a plurality of yarns wrapped helically about the larger core with each of said yarns extending about said larger core adjacent and parallel to each other, and a plurality of different yarns wrapped about the core at the other edge of the braid, said yarns being in braid formation between the two wrappings with the wrapped yarns about the larger core interlocked in braid formation with the braided portion between the wrappings.

3. A cord edge braid comprising a plurality of cores, the core adjacent one edge being larger than the other cores, a plurality of yarns wrapped in helical formation about the larger core with each of said yarns extending about said larger core adjacent and parallel to each other, and a plurality of different yarns wrapped about the core at the other edge of the braid and extending in braid formation between the two wrappings with the wrapped yarns about the larger core interlocked in braid formation with the braided portion between the wrappings, the smaller cores being of equal size whereby a flat braid is provided attached to a generally circular edge portion.

4. A cord edge braid comprising a large core and two smaller cores of the same size in parallel arrangement and next to each other, a set of yarns wrapped in helical formation about the large core, a separate independent set of yarns wrapped about the outer of the smaller cores and braided about the middle core and interlocked in braid formation with the wrapping about the large core.

5. A cord edge braid comprising a flat braid, a core at one edge thereof of a diameter larger than the thickness of said braid, a covering for said core comprising a plurality of yarns helically extending about said core in parallel relation, each of said yarns after a helical wrapping extending along the core in adjacent relation thereto and interlocked with the adjacent edge of the flat braid and thence into the flat braid formation a distance sufficient to be interlaced with the yarns of the braid.

6. A cord edge braid comprising a flat braid, a core at one edge thereof of a diameter larger than the thickness of said braid, a covering for said core comprising a plurality of yarns helically extending about said core in parallel relation, each of said yarns after a helical wrapping extending along the core in adjacent relation thereto and interlocked with the adjacent edge of the flat braid and thence into the flat braid formation a distance sufficient to be interlaced with the yarns of the braid, said flat braid having a core therein of a smaller diameter than the first said core.

7. A cord edge braid comprising a flat braid, a core at one edge thereof of a diameter larger than the thickness of said braid, a covering for said core comprising a plurality of yarns helically extending about said core in parallel relation, each of said yarns after a helical wrapping extending along the core in adjacent relation thereto and interlocked with the adjacent edge of the flat braid and thence into the flat braid formation a distance sufficient to be interlaced with the yarns of the braid, said flat braid having a plurality of cores therein of a smaller diameter than the first said core.
